UNITED STATES PATENT OFFICE.

JOHN ALDEN, OF BOISE, IDAHO.

FRACTIONAL TYPE.

1,178,372.

Specification of Letters Patent.

Patented Apr. 4, 1916.

Application filed November 16, 1915. Serial No. 61,820.

To all whom it may concern:

Be it known that I, JOHN ALDEN, a citizen of the United States, residing at Boise, in the county of Ada and State of Idaho, have invented new and useful Improvements 5 in Fractional Type, of which the following is a specification.

This invention relates to fractional type and it consists in the novel features herein- 10 after described and claimed.

An object of the invention is to provide a device of the character indicated composed of metal, wood or other composition for all 15 sizes of metal or wooden type and the value of the principle involved is incident to the fact that it is practically impossible to secure a full set of fractions, as when a fraction is needed under the present practice it is necessary for the printer to make one 20 and this when done is not satisfactory in view of the fact that it is a makeshift. By using the device hereinafter described, any fraction may be easily and quickly made and 25 in the style of type being used and in as perfect form as a cast one.

The fraction type is a cast device with a bias line on the face thereof, in other words the bias line in the face of the type and the figures to make the fraction are placed in 30 proper position at the opposite sides of the said line in what forms mortised places when set in a line of type. The fraction type may also be used to advantage in composing percentage marks or characters and 35 by using the device the printer is relieved of the necessity of buying fractions with each font. With the present device any fraction can be made by using the figure of the type about two thirds the size of the type being 40 used.

With the above objects in view the device comprises a body having a line disposed across its face and diagonally disposed and disposed upon a bias. Mortises are provided 45 at the opposite sides of the said line and are adapted to receive the type which when placed in the body constitute the fraction to be indicated.

In the accompanying drawings:—Figure 50 1 is a perspective view of the fraction device. Figs. 2, 3 and 4 are detail views.

The fraction device comprises a body 1 which is mortised out at opposite corners

providing spaces 2. The body 1 is provided with a line 3 which is type high and diagonally disposed with relation to the body and which lies between the spaces 2. The line 3 may be curved or straight and when it is in the form of a straight line it is especially adapted to separate the component numbers of a fraction. When the line 2 is curved or provided at its upper end with a stem it may be used for separating the components of a percentage mark or may be used for separating and distinguishing an exponent from a primary number. In practice the body 1 is of the same size as the type which constitutes the font being used and types 4 of about two-thirds the size of the type being used are inserted in the 70 spaces 2. Therefore it will be seen that by employing the body 1 a fraction of any denomination or magnitude may be composed and set up with the body of the type matter. This avoids the necessity of having an 75 excessive number of different fractions in each font of type and when the fractions are composed and appear in the printing they will be regular in appearance and arrangement. 80

From the foregoing description taken in conjunction with the accompanying drawing it will be seen that a device of simple form and arrangement is provided and by using which fractions of different denominations or magnitude may be readily composed and set up in a body of type. 85

Having described the invention what is claimed is:—

A type comprising a body having a type 90 high printing surface, said body being mortised at its side, and a second type body adapted to fit snugly in the mortise and having a type high printing surface, said bodies when assembled having exterior 95 plane surfaces which lie in the same plane thereby forming a type of quadrilateral configuration and which is rectangular in transverse section.

In testimony whereof I affix my signature 100 in presence of two witnesses.

JOHN ALDEN.
